UNITED STATES PATENT OFFICE.

NATHAN H. LAMB, OF FALLOON, MONTANA.

PAPER-HANGING DEVICE.

1,344,906.

Specification of Letters Patent. Patented June 29, 1920.

Application filed March 4, 1919. Serial No. 280,602.

To all whom it may concern:

Be it known that I, NATHAN H. LAMB, a citizen of the United States, residing at Fallon, in the county of Prairie and State of Montana, have invented certain new and useful Improvements in Paper-Hanging Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in devices for hanging paper and consists of a simple and efficient device of this character having various details of construction, combination and arrangement of parts which will be hereinafter fully described, shown in the accompanying drawings and then specifically defined in the appended claim.

My invention is illustrated in the accompanying drawings which, with the letters of reference marked thereon, form a part of this application, and in which:

Figure 1 is a side elevation of the device.

Fig. 2 is a sectional view on line 2—2 of Fig. 1.

Fig. 3 is a detail perspective, showing the application of the paper cutting device, and

Fig. 4 is a detail sectional view showing in edge view the cutter illustrated in Fig. 3.

Reference now being had to the details of the drawings by letter:

A designates the frame of a paper hanging device, which may be of any suitable shape, preferably that shown in the drawings, and which is provided with a handle B. Pivotally mounted in parallel portions of the frame is a reel C, upon which the roll of paper is mounted, and D designates a second reel having a spindle N journaled in the frame, and F is a crank fastened to said reel D. Other rollers designated by

letters H and I are also journaled in the frame and are adapted to frictionally engage the paper which passes between the same. In order to guide the short pieces of paper a bracket member L is fastened to the frame and has a concaved end serving to prevent the paper from moving sideways. In Fig. 4 of the drawings I have shown a bracket arm T fastened to the frame and upon which a movable collar S is mounted having a handle S', and projecting laterally from said collar is a bearing member on which a circular disk cutting knife R is mounted, and which may be utilized for severing the paper when desired by drawing the cutter across the edge of the knife in the manner shown in Fig. 4 of the drawings.

In operation, a quantity of paper is wound from the reel C upon the reel D, after which by moving the disk cutter across the paper it may be severed. One end of the paper is then fed between the rollers H and I and applied to the wall or ceiling which has first been coated with paste, after which by moving the instrument the roller I will press the paper against the wall as it is unreeled. When a section of the paper has been stuck to the wall, the paper may be severed by a knife or other suitable instrument.

What I claim to be new is:

In combination with the frame of a paper hanging apparatus, a bail shaped member secured thereto, and having an end which is disposed at an angle to the frame, a sleeve movable upon said member and having an integral handle projecting therefrom, and a stub shaft also projecting from the sleeve at right angles to said handle, and a cutter disk mounted upon said stub shaft.

In testimony whereof I hereunto affix my signature in presence of two witnesses.

NATHAN H. LAMB.

Witnesses:

W. A. MATTSON,
OLAF CORNELIUSSEN.
